UNITED STATES PATENT OFFICE.

CHARLES K. ERNST, OF BUFFALO, NEW YORK.

CLOSURE FOR AREA WAYS.

Application filed February 17, 1926. Serial No. 88,744.

This invention relates to a closure which is more particularly designed for the upper ends of concrete walls which enclose an area-way, pit or well such as are commonly employed under the side walks adjoining buildings although the same may also be used to advantage in other similar installations.

It has been difficult heretofore to properly secure the frames of such closures in the concrete area-walls and also to prevent water from entering between the frames and the walls and loosening the frame and also running down the inner sides of such walls and making an undesirable mess. The means heretofore employed for pivotally mounting the door of the closure on the frame have also been unsatisfactory owing to the difficulty and expense of such mounting and the liability of the same to get out of order.

The object of this invention is to provide a frame for a closure of this character which is simple and durable in construction and permits of being securely anchored in the concrete and also prevents any water from creeping between the frame and the concrete and loosening the joint between the same and also soiling the inner side of the area-way.

In the accompanying drawings—

Figure 1 is a vertical section of a concrete area-way equipped with my improved closure.

Figure 2 is a top plan view of the same, partly in section.

Figure 3 is a fragmentary perspective view, partly in section, of the closure embodying my invention, the section being taken on line 3—3, Fig. 2.

Figure 4 is a fragmentary vertical section, on an enlarged scale, taken on line 4—4, Fig. 2.

Similar characters of reference indicate like parts in the several figures of the drawings.

The numeral 10 represents the several upright walls enclosing the area-way, pit or well, which walls form a rectangular enclosure and are constructed of concrete.

Embedded in the upper ends of these walls is the frame of the closure which consists generally of metal bars forming channels which open upwardly and provided with means for carrying to a drain any water which may enter the channels. In the preferred organization this frame comprises four angle bars which form a rectangular structure and have their opposing ends con-

nected by electric welding or suitable means, and each of these bars consisting of a vertical inner flange 11 which is flush with the inner side of the respective area-wall and a horizontal lower flange 12 projecting outwardly from the lower end of the vertical flange.

Arranged lengthwise above each horizontal flange between the inner and outer edges thereof is an upright outer metal bar 13 the upper edge of which is slightly higher than the corresponding edge of the vertical inner wall and is flush at its upper edge with the top of the respective concrete wall and the adjacent surface of the side walk or floor. The several upright outer walls engage each other at their opposing ends and are raised slightly from the respective horizontal flanges so as to form a passage 14 therebetween and the same is also spaced apart from the respective vertical inner wall so as to form an upwardly opening channel 15 between these members.

The outer vertical bars of the frame are supported in this position by means which preferably consist of a plurality of spacing sleeves 16 interposed at suitable intervals between the vertical inner flanges and the upright outer bars, and fastening bolts 17 passing through said sleeves and connecting said vertical flanges and upright bars.

Any water entering these channels is carried away to a suitable drain by an upright pipe 18 embedded in the concrete wall 10 and communicating with the channel 15 through an opening formed in one of the horizontal flanges 12. If any water should creep downwardly between the outer side of the outer upright bars and the adjacent part of the concrete such water is conducted inwardly through the passage 14 into the channels and then discharged through the drain outlet of the same.

In order to prevent any water which may come on the horizontal flanges of the frame from flowing outwardly beyond the outer edges of these flanges these edges are turned upwardly slightly, as shown at 20. By this means a curb is formed on the horizontal flange which prevents any water from entering the concrete at these places and thus avoids the possible destructive effect of freezing water in the joint between the frame and the concrete and not only injuring the concrete but also loosening the frame. Moreover the curb on the horizontal flanges also

serves to securely anchor the frame against displacement in the concrete.

Extending over the frame is a door, lid or cover 21 preferably of heavy sheet metal which is scored or checkered on its upper side to prevent slipping thereon. This door rests with its marginal part upon the depressed upper edge of the inner vertical flange and has its edge surrounded by the upper parts of the outer upright bars of the frame so that the upper side of the door is flush with the top of the concrete floor or sidewalk and the edges of the door terminate over the channels of the frame and therefore direct any water falling on the door into these channels from which latter the same is discharged to the drain.

This door may be mounted in any suitable manner to permit of opening and closing the same but this is preferably accomplished by means of a hinge bar 22 arranged lengthwise in one of the channels and secured to the underside of the adjacent edge portion of the door by means of rivets 23 and provided at its opposite ends with trunnions 24 which are journaled in bearing openings 25 in the upright outer bars of the adjacent channels which communicate with the channel containing the hinge bar. The form of pivotal mounting for the door permits of swinging the same vertically into an open and closed position. The same is simple and compact in construction and it is not liable to get out of order when subjected to rough usage. If desired the door may be strengthened by providing its underside with one or more stiffening ribs or cleats 26.

I claim as my invention:—

1. A frame for the closure at the upper end of a concrete area-wall, comprising angle bars each having a vertical inner flange and a lower horizontal flange projecting outwardly from the lower edge of said vertical flange, and upright bars arranged above said horizontal flanges and separated from the same and said vertical flanges to form upwardly opening channels between said upright bars and vertical flanges and passage between the lower edges on said upright bars and said horizontal flanges.

2. A frame for the closure at the upper end of a concrete area-wall, comprising angle bars each having a vertical inner flange and a lower horizontal flange projecting outwardly from the lower edge of said vertical flange, upright bars arranged above said horizontal flanges and separated from the same and said vertical flanges to form

upwardly opening channels between said upright bars and vertical flanges and passage between the lower edges of said upright bars and said horizontal flanges and means for supporting said upright bars on said vertical flanges.

3. A frame for the closure at the upper end of a concrete area-wall, comprising angle bars each having a vertical inner flange and a lower horizontal flange projecting outwardly from the lower edge of said vertical flange, upright bars arranged above said horizontal flanges and separated from the same and said vertical flanges to form upwardly opening channels between said upright bars and vertical flanges and passage between the lower edges of said upright bars and said horizontal flanges and means for supporting said upright bars on said vertical flanges comprising a plurality of spacing sleeves interposed between said vertical flanges and upright walls and bolts connecting said vertical flanges and upright bars and passing through said sleeves.

4. A frame for the closure at the upper end of a concrete area-wall, comprising angle bars each having a vertical inner flange and a lower horizontal flange projecting outwardly from the lower edge of said vertical flange, and upright bars arranged above said horizontal flanges and separated from the same and said vertical flanges to form upwardly opening channels between said upright bars and vertical flanges and passage between the lower edges of said upright bars and said horizontal flanges the outer edges of the horizontal flanges being turned upwardly.

5. A frame for the closure at the upper end of a concrete area-wall, comprising angle bars each having a vertical inner flange and a lower horizontal flange projecting outwardly from the lower edge of said vertical flange, upright bars arranged above said horizontal flanges and separated from the same and said vertical flanges to form upwardly opening channels between said upright bars and vertical flanges and passage between the lower edges of said upright bars and said horizontal flanges, a hinge bar arranged in one of said channels and pivoted at its ends on the upright bars of adjacent channels, and a door secured to said hinge bar and adapted to extend over said frame.

In testimony whereof I hereby affix my signature.

CHARLES K. ERNST.
